UNITED STATES PATENT OFFICE.

JASON B. MOODY, OF DALLAS, TEXAS.

CALCULATING DEVICE.

1,232,066.

Specification of Letters Patent.

Patented July 3, 1917.

Application filed September 30, 1914. Serial No. 864,213.

To all whom it may concern:

Be it known that I, JASON B. MOODY, a citizen of the United States, residing at the city of Dallas and State of Texas, have invented a new and useful Calculating Device, of which the following is a specification.

This invention relates to calculating devices of the type which include a calendar for determining the number of days between two dates, and which also include series of result-tables containing the results of calculations based upon the different periods of time or numbers of days so determined.

The present invention is an improvement in that type of calculating devices constituting the subject-matter of my former Patent No. 1,060,997, dated May 6, 1913.

A specific object of the present invention is to equip the calculating device with improved means for indicating various selected days in various months of the year, so that all of the selected days will be plainly designated within the view of the operator without the necessity of operating the machine to bring the dates of the days successively into view of the operator.

Another object of the invention is to provide improved mechanism for determining and indicating the number of days between given dates, and in which mechanism the indicating device designating the days of the month is movable and adjustable with respect to the part containing the names of the months.

Other objects and many advantages of my invention are apparent in the following description in which reference is made to the accompanying drawings forming a part hereof, and in which—

Figure 1 is a plan view showing a portion of the complete calculator with the devices for indicating the various selected days in the months of different years embodied therein.

Fig. 2 is a vertical sectional view of the calculating device.

Fig. 3 is an enlarged section approximately on the line 3—3 of Fig. 2 illustrating the construction and arrangement of the devices by which the result-tables are pivotally supported in the machine convenient for independent manipulation and for independent removal.

Fig. 4 is a perspective view of one of the arms to which the result-tables are pivotally connected in the machine.

Fig. 5 is an enlarged sectional view taken approximately on the line 5—5 of Fig. 2 illustrating the device for manipulating one of the members provided for indicating special days within a year.

Fig. 6 is a side elevation further illustrating the arrangement of the manipulative device shown in Fig. 5.

Some of the features of the calculating device or machine in which I have illustrated my present invention constitute the subject-matter of my aforesaid Patent No. 1,060,997, dated May 6, 1913. In order to afford a complete understanding of the subject-matter of the present invention it is only necessary to mention generally the features disclosed in said patent with which my present improvements are co-operatively combined and organized.

The machine includes a supporting frame or case 1 preferably composed of sheet metal. The said frame 1 is supported in an oblique position by legs 2, so that the entire upper surface of the machine will be supported in a plane approximately at right angles to the line of vision of the operator, thus bringing all of the essential parts of the machine to which the operator must refer, into plain view. The side wall or periphery 3 of the frame 1 is flared upwardly and outwardly, and to the upper edge thereof is secured a ring 4. The ring 4 is detachably secured to the upper edge of the wall 3 by screws 5, so that the machine may be conveniently separated into its constituent parts for any of the purposes necessitating such separation. The upper surface of the ring 4 is in an oblique plane substantially at right angles to the line of the vision of the operator, and is divided into twelve spaces 6 conforming to the months of the year. Within each space is the name of the corresponding month.

A ring 7 is seated upon an inwardly extended portion 8 in connection with the ring 5, and is retained permanently in position by means of removable screws 9 passing through slots 10 in said ring 7 and engaged in the supporting part 8. The ring 7 is thus enabled to move, the degree of movement being limited by the length of the slots 10 through

which the screws 9 pass. The upper surface of the ring 7 is divided into radial spaces by suitable demarcations clearly illustrated in Fig. 1, and the days of the months are inscribed opposite said demarcations as indicated at 11 in Fig. 1. It will be understood that the illustration of the days of the months in Fig. 1 is conventional, and that the days for all of the months appear upon said ring 7 opposite the names of the months.

The upper surface of the ring 7 is flush with and throughout is in the same plane with the upper surface of an upwardly extended portion 12 which is in connection with the supporting part 8 on which the ring 7 is mounted. The upwardly extended portion 12 is provided with radial demarcations 13 adapted to register with the demarcations constituting the date lines upon the ring 7. One or more of the radial lines 13 within each week period is made more prominent by a suitable configuration 14. In the specific embodiment shown there are two of the lines 13 within each week so indicated, and the chosen form of special demarcation is a diamond shaped device, though it is obvious that other suitable expedients may be employed as preferred. The ring 7 being movable with respect to the part 12 as well as with respect to the names of the months, it is obvious that the movable date ring 7 may be adjusted with respect to the demarcations 14 as to designate all of the Sundays or Saturdays, or other selected days within the same year. The slight movement required by the ring 7 to indicate the selected days within any given year, results in no inconvenience even though the first or last days of the month, as indicated upon the ring 7, may be beyond the lines defining the month spaces 6.

An annular groove is formed in the upper side of the ring 4, and a ring 15 is seated in said groove. The upper surface of the ring 15 is flush with the upper surface of the portion on which the month spaces 6 are formed, and is also in the same plane with the upper surface of the ring 7. The ring 15 is movable with respect to the ring 4 and also with respect to the ring 7. For the purpose of moving the ring 15 I provide a manually engageable member 16 passing through a slot 17 in the peripheral portion of the ring 4, and having threaded engagement with said ring 15. Thus the member 16 constitutes a handle for revolving the ring 15, the extent of movement being limited only by the length of the slot 17, and said member 16 also prevents the ring 15 from becoming detached from the machine. The upper surface of the ring 15, which is in the same plane with the month spaces 6 and with the ring 7, is provided with radial demarcations 18 adapted to register with the radial date lines on the line 7. As in the

case of the demarcations on the raised portion 12, one or more of the radial lines 18 within each week period are made more prominent by suitable configurations 19. The configurations 19 are of the same shape as the special configurations 14. It is preferable that they be of a color which is distinctive from the color of the marking devices 14, for the purpose of avoiding confusion. The ring 15 being movable with respect to the ring 7 and the part 12, as well as with respect to the month spaces 6, it is obvious that said ring may be adjusted with respect to the date ring 7 so as to designate all of the Sundays or Saturdays, or other selected days, within a year previous to or after the year the special days of which are designated by the indicating devices on the raised portion 12. Thus, the spaces 14 on the raised part 12 may be employed to indicate the special days within the present year, for instance, such indication being effected by adjusting the ring 7 in proper position to bring the special days thereon which are to be designated opposite the marking devices 14. Then by adjusting the ring 15 with respect to the ring 7 the special days of the previous year or the succeeding year will be indicated by the special marks 19.

A revoluble frame for supporting the result tables and for coöperating with the calendar members above described, is supported within the supporting frame or case 1. In the embodiment illustrated the supporting frame includes a hub 20 mounted upon an axial member 21 removably secured to the frame 1 by clamp nuts 22. The upper extremity of the member 21 is threaded and is engaged with a nut 23 which is arranged to prevent removal of the hub, but to permit the free and independent rotation thereof. The lower portion of the hub 20 is provided with a circular flange 24 to which is secured the light sheet metal plate 25. The plate 25 is formed with a number of pairs of down-turned ears, which may be made by cutting and bending downwardly the needed portions of the plate 25. Between each pair of ears 26 a roller 27 is journaled, and the said rollers operate within an annular track 28 formed by depressing an annular portion of the frame 1. Near the periphery of the flange 28 is a raised part 29, which constitutes an annular support for the inner ends of all of the result tables in the machine, as illustrated in Fig. 2.

The plate 25 is provided with an upturned portion 30 to the upper edge of which is secured a ring 31. The ring 31 is supported in connection with the upturned portion 30 by means of removable screws 32. To the upper surface of the ring 31 is secured a ring 33 which is in the same plane

with the upper surface of the adjacent raised portion 12 and the other coöperating portions of calendar mechanism mounted on the ring 4. The ring 33 is detachably secured to the ring 31 by screws 34, and the upper surface of said ring 33 is provided with 365 radial lines numbered consecutively from "1" to "365." An arrow 35 is formed adjacent to the radial line 1 so that when it is desired to ascertain the number of days between two dates within a year, the desired result may be quickly and readily accomplished. The number of days between any two dates within a year will be plainly indicated to the operator by placing the arrow 35 opposite the first of the two dates, since the number upon the ring 33, which is opposite the latter of the two dates, will be the number of days between said dates.

For each of the day numbers upon the ring 33 a table 36 is provided, said tables containing calculations in any desired line of business, which calculations have direct reference to or are predicated upon the number of days to which said tables respectively conform. These tables are pivotally supported and are provided with upwardly extending tabs 37 adapted to be manually engaged, whereby any selected table may be raised upwardly to present the calculations thereon to the view of the operator. Preferably each of the tabs 37 is provided with a hole 38 adapted to receive any suitable implement smaller than the fingers of the operator, so that any selected table may be raised without bending or defacing the tabs on the adjacent tables. To the ring 31 are secured a series of radial arms 39 extending inwardly, and the upper edges of which are in approximately the same plane as the upper surface of the ring 33. The arms 39 may be secured to the ring 31, as shown, first by being seated within notches in the ring 31, and then pouring metal within an annular passage through the arms 39 and the intermediate portions of the ring 31, the subsequently cooled metal forming a ring 40 which constitutes a substantially integral bond or union between the arms 39 and the ring 31. The arms 39 are provided with annularly alined holes 41 adapted to receive the pivot members for supporting the result tables.

In the embodiment shown two resilient plates 42 are secured to each result-table, preferably by eyelets 43, the said resilient arms extending obliquely away from each other beyond the edge of the result-table to which they are secured. The extended portions of the resilient plates are adapted to be received between the supporting arms 39, and said arms are pressed out to form projections 44. The projections 44 are received within the holes 41 in the manner illus-

trated in Fig. 3, thus pivotally uniting the result-tables with their supports in such a manner that each result-table is independently operable and independently detachable.

The result-tables may contain any desired results of calculations having reference to the day numbers to which they respectively conform.

I do not restrict myself to the employment of any particular class of calculations, nor to any particular uses, but desire to claim my invention irrespective of the use to which it may be applied.

What I claim and desire to secure by Letters Patent is:

1. In a device of the character described, the combination of a stationary support, an annular series of rigidly located designated spaces corresponding to the months of the year formed on said support, a ring movably supported by the support adjacent to said series of spaces, radial lines formed on said ring corresponding to the days of the months respectively, an additional ring movably supported by said support adjacent to the first-named ring, numbered radial lines on said additional ring corresponding to the days of the months respectively, another series of radial lines adjacent to said additional ring also corresponding to the days of the months respectively, a movable support mounted on the stationary support, and means for coöperating said movable support with said additional ring and with said numbered radial lines to indicate the number of days between any selected dates less than one year apart.

2. In a device of the character described, the combination of a stationary support, an annular series of rigidly located designated spaces corresponding to the months of the year formed on said support, a ring movably supported by the support adjacent to said series of spaces, radial lines formed on said ring corresponding to the days of the months respectively, an additional ring movably supported by said support adjacent to the first-named ring, numbered radial lines on said additional ring corresponding to the days of the months respectively, a movable support mounted on the stationary support, and means for coöperating said movable support with said additional ring and with said numbered radial lines to indicate the number of days between any selected dates less than one year apart.

3. In a device of the character described, the combination of a stationary support, an annular series of rigidly located designated spaces corresponding to the months of the year formed on said support, a ring movably supported by said support within said series of designated spaces, numbered radial lines on said ring corresponding to the days

of the months respectively, another series of radial lines adjacent to said ring also corresponding to the days of the months respectively, a movable support mounted on the stationary support, and means for co-operating said movable support with said ring and with said radial lines to indicate the number of days between any selected dates less than one year apart.

10 4. In a calculating device, the combination of a stationary annular support, an annular series of designated month spaces rigid on the stationary support, a ring movably mounted on the stationary support, radial lines on said ring corresponding to all of the days of all of the months designated in said month spaces, an additional ring movably mounted on the stationary support, numbered radial lines on the additional ring

15 corresponding to the days of the months respectively, means for adjusting one of said rings relative to the other, a result carrier, results of computations on said carrier having reference to the number of days to which

20 said rings respectively correspond, and means for co-operating the result carrier with said additional ring and with said numbered radial lines to indicate the results

25 on said carrier that correspond to the respective number of days between any two

30

dates indicated by any of said numbered radial lines.

5. A calculating device, comprising a stationary support, a ring movably mounted on the stationary support, designated month spaces rigid on said support, radial lines on said ring corresponding to the days of the months, an additional movable ring on said support, numbered radial lines on said additional ring co-operating with the radial lines on the first-named ring to indicate the numbers of the days of the months respectively, a rigid part on said stationary support provided with radial lines corresponding to all of the days of the year, a result carrier, results of computations on said carrier having reference to the number of days indicated by said rings and said radial lines, and means for indicating any result total that corresponds to the number of days between any dates indicated by the radial lines.

In witness whereof, I have signed this specification in the presence of two subscribing witnesses.

JASON B. MOODY.
